LOUD SPEAKERS BAFFLE

Leonard Carduner, Roslyn Heights, N.Y., assignor to
Wharfedale Audio Products, Inc., Port Washington,
N.Y., a corporation of New York

Filed Nov. 4, 1957, Ser. No. 48,342

Term of patent 3½ years

(Cl. D26—14)

FIG. 1

FIG. 2

FIG. 3

FIG. 4

Fig. 1 is a perspective front view partly seen from the side showing my design of a loud speakers baffle.

Fig. 2 is a plan view of Fig. 1.

Fig. 3 is a side view of Fig. 1.

Fig. 4 is a perspective rear view partly seen from the side.

I claim:

The ornamental design for a loud speakers baffle, as shown.
